UNITED STATES PATENT OFFICE

94,999

DESIGN FOR LEATHER OR SIMILAR MATERIAL

Abraham Stern, Averne, Long Island, N. Y.

Application January 28, 1935, Serial No. 55,107

Term of patent 3½ years

To all whom it may concern:

Be it known, that I, Abraham Stern, a citizen of the United States, residing at Averne, Long Island, in the county of Queens and State of New York have invented a new, original, and ornamental Design for Leather or Similar Material, of which the following is a specification, reference being had to the accompanying drawing, forming a part thereof.

Fig. 1 is a face view of a piece of leather or similar material showing my new design.

Fig. 2 is a similar view of the same but on a large scale for purposes of bringing out details of ornamentation.

Fig. 3 is a sectional view taken on the line 3—3 of Fig. 2.

I claim:

The ornamental design for leather or similar material substantially as shown and described.

In testimony whereof I have affixed my signature.

ABRAHAM STERN.
